UNITED STATES PATENT OFFICE.

MARTIN L. SENDERLING, OF JERSEY CITY, NEW JERSEY.

DESIGN FOR A FIFTH-WHEEL SUPPORT.

SPECIFICATION forming part of Design No. 32,197, dated February 6, 1900.

Application filed October 28, 1899. Serial No. 735,130. Term of patent 14 years.

To all whom it may concern:

Be it known that I, MARTIN L. SENDERLING, a citizen of the United States, and a resident of Jersey City, in the county of Hudson and State of New Jersey, have invented and produced a new and original Design for a Fifth-Wheel Support, of which the following is a specification.

The leading feature of my design consists in a fifth-wheel support for vehicles, presenting when viewed in plan a Latin cross and when viewed in side elevation an irregular T.

Figure 1 represents a plan view of the mechanism, and Fig. 2 represents a view of the same in side elevation.

Λ represents the upright of the cross, and

B the horizontal part. The upright is shown as bifurcated at one end, presenting the branches aa' , and gradually reduced in width at the opposite end.

20

What I claim is—

The design for a fifth-wheel support, substantially as herein shown and described.

In testimony that I claim the foregoing as my invention I have signed my name, in presence of two witnesses, this 24th day of October, 1899.
